UNITED STATES PATENT OFFICE

ALFRED G. KERNIN, OF MOSINEE, WISCONSIN, ASSIGNOR TO MOSINEE PAPER MILLS COMPANY, OF MOSINEE, WISCONSIN, A CORPORATION OF WISCONSIN

WATER HEATER

Application filed April 2, 1928. Serial No. 266,704.

This invention relates to a heat economy apparatus and more particularly to apparatus for utilizing the waste heat contained in steam blown off from digesters in pulp making processes.

In the manufacture of pulp, large volumes of steam are liberated during the intermittent blowing off periods occurring at the end of the cooking of each successive batch of 10 chips. In sulphate pulp mills especially, the steam is of a peculiarly offensive odor and, owing to its contamination, the steam, or condensate therefrom, is rarely used in subsequent operations, but is either vented to the 15 atmosphere or blown into a jet condenser for discharge into the sewer.

There is little use made, therefore, of the steam for producing hot water for pulp washing purposes on account of the inferior 20 quality of the water that can be made. Furthermore, owing to the intermittent character of the blowing operations, if the water used in condensing the steam is circulated continuously, the resulting water will fluctuate too 25 widely in temperature to be satisfactory for washing purposes.

According to my invention, however, the waste steam is condensed in a heat economy apparatus by direct contact with constantly 30 circulating water and water for washing purposes is then indirectly heated from the directly heated water. In this way no contamination of the water for washing can occur.

It is therefore an object of this invention 35 to provide a heat economy apparatus for effectively utilizing the waste heat from steam to produce an uncontaminated water for washing purposes.

Other and further important objects of 40 this invention will be apparent from the disclosures in the specification and the accompanying drawings.

This invention (in a preferred form) is illustrated in the drawing and hereinafter 45 more fully described.

On the drawing:

The figure is an elevational view with parts broken away and in section, of apparatus embodying the principles of my invention.

The reference numeral 1 indicates a tank, preferably cylindrical in form, with a dished bottom 2 and a dome 3 extending from the top thereof. A pipe 4, in the side of the dome 3, serves for the introduction of steam which 55 is mixed in the dome with water to be heated thereby. In the pulp mill, to which my invention is particularly directed, the steam entering through the pipe 4 is steam, liberated during the blowing-off of a digester. 60 The flow of steam, therefore, through the pipe 4 is intermittent and in great volume for short periods only.

An outside circulating system comprising a pump 5 connected on its intake side to a 65 pipe 6 leading from the bottom of said tank 1 and on its discharge side to a pipe 7 connected into the top of the dome 3 as at 8 serves to circulate water through the tank 1. This water in circulating, mixes with and 70 condenses steam introduced through the pipe 4, thereby raising the temperature of the water to any desired point. Fresh water may be admitted into the circulating system from a main line 9 through the piping 10 controlled 75 by a valve 11. Although the water thus directly heated by the steam becomes contaminated with entrained products from the digestion processes, it is yet suitable for general heating purposes. Valve controlled connections 12 and 13 serve for the diversion of a part of the heated water for any outside 80 heating installation.

A barometric jet condenser 14 is connected to the tank 1 by means of a pipe 15 having an 85 upturned elbow 16 opening above the level of the water within the tank 1.

The condenser 14 thus serves to take care of any excess uncondensed steam in the tank 1. Water is fed into the jet condenser 90 through a valve controlled pipe 17 leading from the main pipe 9. The leg of the condenser extends into a sewer pipe or the like. A piping connection 18, having a valve 19 therein, serves as a drain from the tank 1 95 whenever it becomes necessary to drain the contents of said tank. The level of the water in the tank 1 is maintained by reference to a sight glass 20 and may be reduced to the proper level by draining off through a con- 100

densate line 21 having a valve 22 positioned therein.

In order to utilize the heat of the steam condensed by the water in the tank 1, a plurality of closed coils 23 are supported from the bottom of said tank by means of supports 24. Water for washing purposes is introduced into said coils 23 by opening a valve 25 in a pipe 27 leading to said coils from a source of fresh water. The heated water from said coils 23 is taken off from the upper coil through a pipe 26 leading to diffusers, or, wherever the hot water is to be used for washing. Inasmuch as this water is not brought into direct contact with the heated water in the tank 1, it is sufficiently pure for washing purposes. By reason of the relatively large volume of water within the tank 1, the temperature to which the water for washing purposes is heated can be maintained practically constant. A plentiful supply of hot water is thus furnished at practically no cost and at a considerable saving over the usual practices.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. A heat economy apparatus for use in the manufacture of pulp, comprising a tank having a mixing dome, means for introducing blow-off steam into said dome, an outside circulating system for drawing water from the bottom of said tank and introducing said water into the top of said dome to condense said steam and be heated thereby and closed pipe coils positioned in said tank for heating water circulated through said coils.

2. A heat economy apparatus for use in the manufacture of pulp, comprising a tank having a mixing dome, means for introducing blow-off steam into said dome, an outside circulating system for drawing water from the bottom of said tank and introducing said water into the top of said dome to condense said steam and be heated thereby, closed pipe coils positioned in said tank for heating water circulated through said coils, and a barometric jet condenser associated with said tank for condensing steam vapors remaining uncondensed in said tank.

3. A heat economy apparatus for utilizing the heat of steam produced in the blowing of sulphate pulp digesters, comprising a tank having a mixing dome, means for introducing blow-off steam into said dome, an outside circulating system for drawing water from the bottom of said tank and pumping said water into the top of said dome to condense said steam, closed coils within said tank for

the circulation of water to be indirectly heated and valved connections in said outside circulating system for diverting some of the direct heated water for heating purposes.

4. A water heater for use in pulp mills for utilizing the heat value of the steam and gases blown off from pulp digesters, comprising a tank adapted to be partially filled with water, means for withdrawing water from said tank and discharging it back into said tank above the level of the water therein, means for introducing the steam and gases blown off from a pulp digester into said tank in the path of the water discharged thereinto to condense said steam thereby and means for conducting a liquid to be heated through said tank without contamination by direct contact with the water therein.

In testimony whereof I have hereunto subscribed my name.

ALFRED G. KERNIN.
